UNITED STATES PATENT OFFICE.

THOMAS M. DANIELS, OF LATROBE, PENNSYLVANIA.

RAIL-JOINT.

1,210,430.

Specification of Letters Patent.

Patented Jan. 2, 1917.

Application filed January 19, 1915. Serial No. 3,137.

To all whom it may concern:

Be it known that I, THOMAS M. DANIELS, a citizen of the United States, residing at Latrobe, in the county of Westmoreland and State of Pennsylvania, have invented a new and useful Rail-Joint, of which the following is a specification.

This invention relates to rail joints and more especially to a new and improved form of fish plate designed for use in connection with rails whereby the said rails can be securely braced and can be held together without the necessity of using bolts and like fastening devices.

15 A further object is to provide a fish plate which is adapted to be secured in position by spikes of the usual form.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, can be made within the scope of what is claimed, without departing from the spirit of the invention.

In the accompanying drawings the preferred form of the invention has been shown.

In said drawings:—Figure 1 is a side elevation of a rail joint having the present improvements combined therewith. Fig. 2 is a plan view of the fish plates, the rail 35 being shown in section. Fig. 3 is a section on line A—B Fig. 2.

Referring to the figures by characters of reference 1 designates the transversely inclined base of the fish plate designed to 40 rest upon one of the base flanges of a rail and this base has wings 2 extending laterally therefrom, the bottom faces of the wings being adapted to rest flat upon the ties. These wings can be of any shape de- 45 sired and each of them is formed with an enlargement 3 upon its upper face which enlargement extends to an upstanding flange 4 which is disposed longitudinally along the inner or active side of the base 1. 50 This flange is adapted to fit snugly against the webs of the rails and the enlargements 3 are integral with the flange. It will be

noted furthermore that the flange not only engages one side of the web of a rail but also projects upwardly into engagement 55 with the lower face of the head of the rail. This is shown particularly in Fig. 3.

By providing a structure such as described the engaged rail is thoroughly braced and, as the head of the rail is supported, there is no danger of the rail sagging at its ends and causing the wheels to pound while passing over the joint.

Spike receiving openings 5 are formed in the base 1 close to each side of each enlargement 3 and another spike receiving opening 6 is formed in each wing 2 adjacent the outer end of the enlargement thereon.

In using the fish plates they are placed at opposite sides of the meeting end portions of the rails R and after being pressed tightly against the rails, they are secured by driving spikes, not shown, through the openings 5 and 6. Thus the fish plates are held against displacement and the rails are 70 both clamped tightly between the fish plates and supported so that displacement of the rails relative to each other is prevented without the use of bolts such as heretofore required.

80 Each fish plate can be rolled, stamped or cast as desired and, as the braces formed by the enlargements 3 are integral with the fish plates, it is not necessary to use any special fastening means for holding the said braces 85 in place.

What is claimed is:—

The combination with alining rails, of opposed base plates for engagement with the ties supporting the rails, said base plates 90 having their inner portions inclined and bearing upon the base flanges of the rails, an upstanding longitudinal flange along the inner edge of each base plate and engaging one side of the rail webs, these 95 flanges extending under and engaging the heads of the rails, wings extending laterally from the base plates, braces upon each of the base plates integral with the wings and base plates and substantially equal 100 in width to the wings, said braces being integral with the upstanding flanges and having their upper faces disposed in a plane below the upper edges of the flanges,

there being spike receiving openings close to the sides of the braces and at the outer end of each brace, the outer end of each brace being adapted for engagement by the head of a spike within the adjacent opening.

In testimony that I claim the foregoing

as my own, I have hereto affixed my signature in the presence of two witnesses.

THOMAS M. DANIELS.

Witnesses:

A. H. BELL,

GEO. E. BARRON.
